DISASTER ALARM CABINET

James L. Kissel, 2204 Cedar Drive,
Rapid City, S. Dak. 57701

Filed Sept. 2, 1975, Ser. No. 609,398

Term of patent 14 years

Int. Cl. D10—06

U.S. Cl. D10—106

Fig. 1

Fig. 2

Fig. 3

Fig. 4

Fig. 5

FIG. 1 is a perspective view of the disaster alarm cabinet showing my new design;

FIG. 2 is a rear elevational view thereof on a reduced scale;

FIG. 3 is a side elevation thereof with the opposite side being a mirror image thereof on a reduced scale;

FIG. 4 is an end view thereof on a reduced scale; and,

FIG. 5 is the opposite end view.

The small square apertures in the lower front of the cabinet are indicated by partial cross-hatching in FIG. 4 for convenience of illustration.

I claim:

The ornamental design for a disaster alarm cabinet, as shown and described.
